CLAIM

The ornamental design for a hanging living wall planter, as shown and described.

DESCRIPTION

FIG. 1 shows a perspective view of a hanging living wall planter.

FIG. 2 shows a front view of a hanging living wall planter.

FIG. 3 shows a back view of a hanging living wall planter.

FIG. 4 shows a side view of a hanging living wall planter.

FIG. 5 shows a side view of a hanging living wall planter.

FIG. 6 shows a top view of a hanging living wall planter.

FIG. 7 shows a bottom view of a hanging living wall planter; and,

FIG. 8 shows an exploded view of a hanging living wall planter.

The evenly dashed broken lines in the illustrations are directed to environment and are for illustration purposes only; the evenly dashed broken lines form no part of the claimed design. The portions of FIG. 8 drawn in uneven dot-dot-dash lines show instructional indicia **15** and form no part of the claimed design. The portions of the article not shown form no part of the claimed design.

1 Claim, 4 Drawing Sheets
